UNITED STATES PATENT OFFICE

ALWIN G. STEINMAYER, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS

END BELL

Application filed March 21, 1933. Serial No. 636,483.

My invention relates to cable end bells and the like.

In the installation of devices of this sort, the cable is led into the bell where its sheath is peeled back or removed and its individual conductors separated. The separated conductors are joined to the aerial or other conductors to which connection is desired, usually through terminal means associated with the bell. The matter of establishing proper electrical and mechanical connection between the separated cable conductors and said terminal means has presented a difficult problem. Where any of the cable conductors are cut off too short, which is almost impossible to avoid, connection with the terminal has either been impaired or made impossible.

Where the conductors are too long the resulting slack will permit the conductors to be swung by the flow of current, apart or together, depending upon the relative directions of current flow in the conductors. In high tension work the conductors will, if there is slack in them permitting it, be swung within the bell with great force. This swinging of the conductors within the bell stresses the soldered joints between them and the terminal studs and causes air blisters or bubbles in the insulating compound within the bell. In cold weather the compound may be cracked thereby. Air blisters or bubbles in or cracking of the compound permits ionization of the air in the blisters or cracks, corona effects therethrough and a breaking down of the entire equipment. It is important that the compound cover the conductors uniformly and that air blisters and the like in the compound be avoided.

Another problem has been in properly clamping the terminal itself in place. A joint that will prevent the entrance of moisture is required. The entrance or absorption of moisture would damage the insulation and decrease the insulating resistance with the likelihood of a break-down from short-circuiting or burning out of the cable. Where the terminals are mounted at the outer ends of lead-out insulators, distribution and minimization of the stresses upon the insulator and connection and sealing parts must be

taken into consideration in clamping the terminals in place.

An object of my invention is the provision of an improved lead-out connection for clamping the terminal in place and securing proper electrical and mechanical connection with the cable conductor in spite of variations in cutting. 55

Another object is the provision of a tight outlet joint for preventing the entrance of moisture. 60

Another object is to avoid imposing mechanical stresses upon the conductor and where the connection is clamped upon a lead-out insulator, to minimize the stresses upon the insulator, cap piece and associated connection parts. 65

Another object is the provision of improved mounting means for mounting the bell in various positions and upon various types of supports. 70

Another object is the provision of a mounting that will accommodate itself to variations in the positioning of the attaching means.

The provision made for clamping the terminal in place and securing proper electrical and mechanical connection with the conductor to which connection is desired in spite of variation in cutting, as where said conductor is cut short, as is frequently the case, is one of the chief advantages of the invention. According to this phase of the invention, an adjustable take-up plug is provided for adjusting the position of the terminal for proper connection with the cut-off cable strand and for clamping the terminal in position without stressing the cable strand, the insulator or associated connector parts. 75 80 85

Where the conductor is cut off short, the take-up plug positions the terminal for proper mechanical and electrical connection therewith and provides for securely clamping the terminal in said position. 90

While I shall describe certain embodiments of the invention in connection with certain types of end bells, it is to be understood that the invention is not limited to use with any particular type, but may be employed in connection with other forms of end bells, and in all similar connections. I shall describe 95 100

the terminal connection as a so-called lead-out connection for the separated or individual conductors of the bell. It is to be understood however that the scheme may be used 5 as a lead in connection in other forms of devices.

In order to apprise those skilled in the art with the manner of constructing and practicing my invention, I shall now describe 10 certain specific embodiments of the invention in connection with the accompanying drawings in which:—

Figure 1 is a vertical section through a 15 device embodying the invention;

Fig. 2 is a detail vertical section through the lead-out or aerial connection shown in Fig. 1;

Fig. 3 is a detail elevational view of a 20 key for the adjustable take-up plug shown in Figs. 1 and 2;

Figs. 4 and 5 are similar views of modified forms of lead-out or aerial connections;

Figs. 6 and 7 are detail sections of modified forms of joints that may be used between 25 the cable and the bottom of the bell;

Fig. 8 is a front elevational view of another form of end bell embodying the features of my present invention;

Fig. 9 is a fragmentary side elevational 30 view showing one mounting of the same;

Fig. 10 is a fragmentary side elevational view showing another mounting of the end bell shown in Figs. 8 and 9; and

Fig. 11 is a detail perspective view of the 35 preferred form of socket terminal employed.

In the embodiment shown in Fig. 1 the lead covered cable 5, which is shown as having three conductors 6, is led upwardly from the underground conduit, for example, and 40 into bowl member 8 which forms the main part of the pot head. The lower end of bowl 8 has a flange 9.

In this instance cable 5 is led up through 45 a pipe or conduit 10, the upper end of which has threaded engagement with a flanged member 12. Bolts 14 draw flanges 9 and 12 together with the radially extending flange of sealing or bushing member 15 clamped therebetween. Member 15 has a conical bore 50 to receive a conical wedge ring 16. This ring, which is preferably made of some relatively soft conducting material, is driven firmly into place to ensure good gripping engagement with the cable sheath, permanent grounding and tight sealing against leakage 55 of compound. The lead cable sheath is grounded through wedge ring 16 to prevent static accumulation. Such accumulation on a lead covered or steel-taped cable dissipates itself at the end, and without some sort of effective grounding at that point, would eventually puncture the insulation and result in a breakdown. The upper inner edge 60 of member 16 is rounded or flared out and the cable sheath is rounded or flared out over

said edge, as shown at 18. This binds the cable in place and in addition lessens the electrostatic strains at the end of the cable sheath.

Bowl 8 has an open top and a removable 70 cover 20 is suitably fastened thereover, a suitable gasket being preferably provided to secure a tight joint therebetween. Bowl 8 is provided with integral lugs or ears 22, through which the bowl is adapted to be fastened or mounted on a pole, wall, cross arm 75 or other suitable support. Within bowl 8 the lead cable sheath having been peeled off or removed and flared out over wedge ring 16, conductors 6 are separated and led out through sleeves of insulation 25 to the aerial terminals at the outer ends of insulators 25, which insulators are cemented, as shown at 28 in outlet openings in cover 20.

Bowl 8 is filled with insulating compound 80 up to a point above the lower ends of insulators 25, as shown. This may be done by heating the compound and pouring it in through a filling opening 26 in cover 20.

The aerial connections each comprises a 90 terminal stud 30 soldered or otherwise secured upon the ends of conductors 6, the insulation on said conductors being stripped back just sufficiently to make proper mechanical and electrical connection with the 95 sockets in the inner ends of studs 30. The outer reduced threaded shanks 32 of studs 30 project out freely through cap members 34 cemented upon the upper ends of insulators 25. Cap members 34 have upwardly extending flanges 36 internally threaded at 37 and an externally threaded take-up plug or seating member 38 fits for the terminal stud 30 loosely over each threaded shank 32 and has threaded engagement with cap member 100 34. Upper ends of plugs 38 are provided with key-ways 40 for engagement by a suitable key 41 (Fig. 3) by means of which key 41 plugs 38 are screwed down until they engage the shoulders of studs 30.

Key 41 comprises a sleeve, the lower edge of which is provided with diametrically opposite downwardly extending projections 105 for engagement in key-ways 40. Radial notches 106 at the upper end of key 41 facilitate turning same to thread plugs 38 into or out of cap members 34.

A cap nut 42 threaded down on threaded shank 32 is recessed at its lower end to engage over upwardly extending flange 36, 120 and down into firm engagement with a gasket 43 interposed between the lower edge thereof and cap member 34, to provide with the cementing of cap 34 on insulator 25 a tight joint through which the entrance of moisture 125 is prevented. It is well known that the entrance of moisture would damage the insulation and decrease the insulating resistance with the likelihood of a break-down from short circuiting or burning out of the cable. 130

Threaded upon shank 32 into engagement with cap nut 42 is a contact nut 45 and between said nut 45 and a second contact nut 46 is clamped a socket terminal 48 into the 5 socket portion of which is soldered or otherwise connected, the aerial or other conductors or leads 50 to which connection of conductors 6 is desired.

The socket terminals preferably employed 10 include socket portions 108 and contact portions or mounting bases 109, as shown in Fig. 11. Base 109 is slotted for engagement about shanks 32 and the free ends of jaws or 15 projections 110 are provided with downwardly protruding edges 112 which serve to hold the terminal in place and against unintentional displacement, such as might result from vibration.

From the foregoing it will now be apparent 20 that take-up plugs 38 take care of variations in cutting and soldering of conductors 6 to terminal studs 30, and form seats into engagement with which the terminal studs are properly clamped, notwithstanding 25 variations in the positioning of said studs. If either conductor 6 is cut off short, for example, the end can still be inserted all the way into socket 52 in stud 30 to secure 30 the desired electrical and mechanical connection therebetween, plug 38 being threaded or screwed in to take up the difference and properly seat the shoulder at the upper end of the lower enlarged portion of stud 30. Studs 30 are securely clamped in position 35 without stressing the cable conductors or the insulators 25, caps 34 or associated connector parts and at the same time by holding the conductor out taut in assembly and threading the take-up plug down into engagement 40 with the shoulder on the terminal stud, the conductor will be held taut or at least without sufficient slack to permit the disadvantageous, if not disastrous results referred to at the outset and regardless of variations in 45 length of the conductors. Cap nuts 42 and contact nuts 45—46 with plugs 38 clamp the terminals in place and provide metallic seals at the upper ends of insulators 25.

In assembling, member 12 is screwed 50 tightly onto conduit 10. Cable 5 is pulled out far enough to permit easy trimming and spreading of conductors 6. Grounding collar 15 is arranged over the cable and seated in member 12. The upper end of the lead cable 55 sheath is peeled off, wedge ring 16 inserted and driven firmly into collar 15, and the cable sheath belled out over wedge ring 16 to bind the cable in place and relieve high potential static, and possible injury to the insulation. 60 Conductors 6 are spread out into their approximate relative positions when installation is completed. Terminal studs 30 are removed from insulators 25 by removing cap nuts 42, contact nuts 45—46 and take-up plugs 65 38, and bowl 8 and cover 20 with insulators

25 in place are temporarily placed on member 12, allowing the individual conductors to pass through their respective lead-out insulators. The threaded openings through cap members 34 are preferably sufficiently large 70 to permit pulling the cable strands 6 therethrough and insertion and removal of studs 30 into the upper ends of insulators 25 through said cap members 34.

The projecting conductors 6 are then 75 marked flush with tops of cap members 34, the casing and cover removed and the individual conductors cut off the proper distance below said markings. Take-up plugs 38 permit 80 variations in the cutting of the conductors, which variations have been a considerable problem heretofore. Terminal studs 30 are soldered to ends of conductors 6, bowl 8 and cover 20 with its insulators 25 are replaced, all bolts being drawn up tight to provide 85 tight joints. Take-up plugs 38 are replaced using key 41 to screw them down into proper sealing engagement with studs 30. Gaskets 43, cap nuts 42 and nuts 45—46 are replaced and conductors 50 are secured in terminals 48, the sealing compound being filled in through opening 26.

From the foregoing, it will now be apparent 90 that the take-up plugs assure proper tautness of the conductors through the bell 95 and that they provide adjustable seats for seating the studs 30 properly with variations in the lengths of the conductors. The cap nuts 42 thereupon tension the studs 30 between the nuts 42 and the shoulders on the 100 studs 30 to hold the studs firmly against their seats on the plugs 38 and the conductors firmly in place without stressing the soldered or other joints between the conductors and the studs 30. The cap nuts 42 may be drawn up 105 as tight as desired upon the gaskets shown in Figure 1 between them and the caps 34 to seal the outlets and without stressing the conductors or the joints between them and the studs 30. The connection thus takes up any desirable slack in the conductors and is adjustable 110 for variations in the lengths of the conductors and at the same time the conductors and the joints between them and the terminal studs 30 are not stressed thereby. The upper projecting 115 ends of the threaded shanks of the studs 30 are externally accessible for applying a tool in the slots in the upper ends thereof as shown, or otherwise holding the terminal stud against turning in threading the nuts thereupon. The take-up plug provides a seat upon which the terminal stud 30 may be seated with the conductor drawn taut enough to remove the slack therefrom, yet not stretched sufficiently to stress the joint between the conductor and the terminal stud and this take-up plug is adjustable for adjusting the position of this seat to meet variations in length of the conductor. The stud 30 is tensioned between 120 this adjustable seat and the cooperation of the 125

130

nut 42 with the top of the cap 34 or gasket therebetween to clamp and bind it firmly in place without imposing any pulling, twisting or other stress upon the joint between the 5 conductor and the stud 30.

In Fig. 4 I have shown a modified form of aerial connection in which cap member 34' is cemented upon the upper end of insulating sleeve 25' and the threaded shank 32' of terminal stud 30' extends out therethrough, as 10 before. In this case, the upwardly extending flange 36' of cap member 34' is externally threaded and the lower recessed end of cap nut 42' is internally threaded for threaded 15 engagement therewith, the upper portion of cap member 42' having threaded engagement with shank 32' at 60, as before. The shank 32' is threaded in or out of cap nut 42' to properly position the terminal stud according 20 to the length of cable conductor 6' and contact nuts 45'-46' with terminal 48' clamped therebetween, are drawn up tightly against the cap nut to lock the nut and terminal 30' in place. The cementing of cap member 34' 25 on insulator 25' and the threaded engagement of cap nut 42' with cap member 34' and shank 32' provides a tight joint for preventing the entrance of moisture.

In the modification shown in Fig. 5, cap 30 nut 62, instead of having threaded engagement with cap member 63, is clamped there- 35 to by bolts 65, cap nut 62 and cap member 63 having cooperating flanges 66 and 68 for this purpose.

35 In Fig. 6 I have shown another form of joint that may be used between the cable and the bottom of the bell. In this case the armored cable 5' is unprotected by pipe conduit. A flange ring 70 is clamped to the cable sheath by split clamps 72, one preferably 40 integral with ring 70 and the other clamped about the cable by bolts 74 extending through the clamp members. The armor sheath is peeled off and conductors 6 led out, as before, 45 the upper edge of the sheath being belled out over rounded edge of ring 70 to relieve sharp corners, potential static and possible injury to insulation. Grounding of the cable sheath is had through ring 70 and clamping mem- 50 bers 72.

In Fig. 7 I have shown a wiped joint between the cable and the lower end of the bell. In this case the joint between the bottom of the bell and cable 5 comprises a wiping member 78 attached by bolts 79 to flange 80 at the bottom of the bell. This member 78 has a depending flange 81 which converges into snug engagement at its lower end with the cable sheath and a tight joint is provided 55 therebetween by a wiped solder joint 82, such as is well known in the art. A sealing member and wedge, such as shown in Fig. 1, may be provided in connection with this mounting, if so desired, preferably only where the 60 dimensions of the cable are relatively large.

In Figs. 8 and 9 I have shown the aerial terminals of my invention in connection with an end bell, the bowl 90 of which is formed so that inlet 91 is at a ninety degree angle to the open top 92 over which cover 93 with its 70 lead-out insulators 94 is fastened. This form of pot head is of great advantage where it is desired to run the cable horizontally into the bowl of the pot head.

To permit left or right hand attachment 75 to the wall or other support, that is, attachment with either the front or rear face against the support so that the inlet 91 will extend either to the left or to the right, as desired, the integral mounting ears 95 project 80 from the opposite ends of bowl 90 midway between the opposite faces of the bowl. Mounting lugs 96 secured to ears 95 by bolts 98 have flanges 99 through which bolts or other suitable attachment means are inserted 85 to secure the device to the desired support. With lugs 96 in the position shown, the device is adapted for attachment to a wall or other support to the right of the device (Fig. 9) with inlet 91 extending toward you in 90 looking at said figure. By removing said lugs 96 and attaching same to the other sides of ears 95, that is, by reversing the positions of lugs 96 and bolts 98, the device is adapted 95 for attachment to a support to the left (Fig. 9) with inlet 91 extending away, or in the opposite direction.

The pivotal connection of lugs 96 to ears 95, in either position, permits accommodation 100 to variations in the positioning of the attaching means, as for example, to variations of the positioning of the bolts inserted through the mounting eyes in flanges 99 of said ears 95.

When it is desired to mount the device be- 105 tween two cross arms 100 and 101 (Fig. 10), as is frequently the case, lugs 96 are removed entirely and relatively long mounting bolts 102 are inserted through aligned openings in cross arms 100 and 101 and through the open- 110 ings in ears 95. The free ends of bolts 102 may have threaded engagement with suitable nuts 103 or they may be otherwise secured in place.

From the foregoing, it will now be ap- 115 parent that most any desired positioning and mounting of the angle bell is thus permitted. This is advantageous in that the desired positioning or mounting varies in different in- 120 stallations, and it has heretofore been necessary to make the bell for right or left or cross arm mountings, as desired. When made up for a left hand mounting, the bell could not be mounted right handed and vice versa.

The ninety degree angle shown in Figs. 8, 9 and 10 is simply illustrative of an angle bell. The features of the invention may, of course, be embodied in a bell of different angle, or of the vertical type as shown in Fig. 1, or any 130

other form of bell. While the aerial connections described in connection with Figs. 1, 2, 3, 4 and 5 are especially adapted for use with bells for outdoor service, where the susceptibility to the entrance of moisture is greatest and weather conditions are severest, it is to be understood that such connections may be used in connection with indoor bells, should it be desirable, and the improved mounting described in connection with Figs. 8, 9 and 10, is, of course, equally applicable for indoor or outdoor service.

The making of the connections between the cable conductors and terminal studs provides a high insulating factor of safety.

I claim:—

1. In a terminal structure forelectriccables, the combination of a casing, a tubular outlet member leading therefrom, a conductor extending into said outlet member, a terminal member secured upon the conductor, said terminal member having a shoulder and a threaded shank extending therefrom, a cap member mounted upon the outlet member, a seating member having threaded engagement with said cap member and contact with the shoulder on the terminal member and a nut member threaded upon the shank of the terminal member and contacting said cap member for adjustably clamping the terminal member against said seating member and in place without stressing the conductor.

2. In combination, an outlet member, a cap member mounted thereon, a terminal member having an abutment and a threaded shank, a seating member threaded into said cap member and adapted to contact the abutment on the terminal member, and a nut member threaded upon the shank of the terminal member and having contact with the cap member for clamping the terminal member in contact with said seating member.

3. In combination, an outlet member, a cap member mounted thereon, a terminal member having an abutment and a threaded shank, a seating member threaded into said cap member and adapted to contact the abutment on the terminal member, a nut member threaded upon the shank of the terminal member and having contact with the cap member for clamping the terminal member in contact with said seating member, a pair of nuts threaded upon the shank of the terminal member for locking said last nut member against displacement and a terminal secured between said lock nuts.

4. In combination, an outlet member, a cap member on the end of said outlet member and overhanging the same, a conductor extending into said outlet member, a terminal member disposed in said outlet member and secured mechanically and electrically upon said conductor, and a take-up member adjustably mounted in said cap member and adapted to be adjusted to engage the terminal

member for seating same in different positions and means for clamping the terminal member against said take-up member.

5. In a device of the class described, the combination of an insulating sleeve, closure means and a terminal connection at the outer end of said sleeve, said terminal connection comprising a terminal stud having a shoulder and a threaded shank, a take-up member mounted to be adjusted into contact with the shoulder on the terminal connection in the direction of the length of the conductor and forming an adjustable stop and seat for the terminal connection and a nut threaded upon the shank of the terminal connection and contacting said closure means for clamping the terminal connection in contact with said take-up member.

6. An end bell having an inlet opening and an outlet opening, a sheathed cable extending into the bell through one of the openings, the end of the cable being bared of the sheath, means rigidly securing the sheath to the bell, a terminal secured to the end of the cable within the bell, an insulating compound filling the lower portion of the bell, a hollow insulator extending into the bell through the other opening, said insulator extending into the compound thereby closing communication between the opening and the portion of the bell above the top of the compound, a cap member on the external end of the insulator and sealed thereto, said cap having a projecting flange and said terminal member extending into the opening in the insulator and having a threaded shank extending beyond the insulator cap, a cap nut having threaded engagement with the shank, said cap nut extending over the flange of the cap and providing a closure therefor, a conductor connector, and means including a lock nut for securing the connector to the end of the terminal.

7. In a device of the class described, an insulating sleeve, closure means and a terminal connection at the outer end of said sleeve, said terminal connection comprising a terminal stud having a shoulder and a threaded shank, and means for clamping said stud in place, said means comprising an adjustable take-up plug having threaded engagement with said closure means, and engageable with the shoulder of the terminal stud, and nut means threaded upon the threaded shank and having engagement with said closure means for clamping the terminal stud against the take-up plug.

8. In a device of the class described, the combination of an insulating sleeve, a cap at the end of said sleeve, said cap having a projecting flange, a terminal member mounted in said sleeve and having a threaded shank extending through said cap, a cap nut threaded upon the projecting shank of said terminal member, said cap nut contacting the cap member and recessed to engage

over the projecting flange of said cap, and a take-up member threaded into said cap and having adjustable cooperation with the terminal member.

- 5 9. In a device of the class described, the combination of an insulating sleeve, closure means at the end of said sleeve, said closure means having a projecting flange, a terminal member mounted in said sleeve and having
10 a threaded shank extending through said closure means, a cap nut threaded upon the projecting shank of said terminal member and recessed to engage over the projecting flange of said closure means and to contact
15 the closure means, a contact nut threaded upon the projecting shank of the terminal member into engagement with the cap nut and a take-up member threaded into said closure means and having adjustable cooperation with the terminal member.

10. In a device of the class described, an insulating sleeve, closure means including a cap member, and a terminal connection at the outer end of said sleeve, said cap member having a projecting flange and said terminal connection including a stud having a shoulder and a threaded shank projecting through said cap member, means for clamping said stud in place, said means comprising
25 an adjustable take-up plug having threaded engagement with said cap member and engageable with the shoulder of the terminal stud, and recessed nut means threaded upon said threaded shank and engaging the cap member to clamp the terminal connection against the take-up plug.

11. In combination, a hollow insulator, a cap upon the top of the insulator, a terminal passing through the cap, the cap and
40 terminal having inter-engaging shoulders, an adjustable mounting for one of said shoulders and a cap member seating on said first cap and closing the same, said second cap member having adjustable engagement with
45 the terminal to draw said shoulders into engagement.

12. In combination, a hollow insulator, a terminal projecting through the end of the same, a cap about the end of the insulator
50 through which the terminal projects, means free of the terminal member for adjusting the position of the terminal in the cap and means for clamping the terminal against said adjusting means.

- 55 In witness whereof, I hereunto subscribe my name this 15 day of March, 1923.

ALWIN G. STEINMAYER.
